UNITED STATES PATENT OFFICE.

WILLIAM R. ALLEN, OF CLEVELAND, OHIO, ASSIGNOR TO THE AMERICAN MULTIGRAPH COMPANY, OF CLEVELAND, OHIO, A CORPORATION OF OHIO.

TYPE-BAR.

1,078,401.

Specification of Letters Patent. Patented Nov. 11, 1912.

Application filed November 6, 1912. Serial No. 726,743.

To all whom it may concern:

Be it known that I, WILLIAM R. ALLEN, a citizen of the United States, residing at Cleveland, in the county of Cuyahoga and State of Ohio, have invented a certain new and useful Improvement in Type-Bars, of which the following is a full, clear, and exact description, reference being had to the accompanying drawings.

10 One of the objects of this invention is to provide type bodies (including line slugs, logotypes and individual type) in a form which may be conveniently and efficiently mounted about a drum parallel with the axis thereof and will firmly seat thereon but will not work up from the seat as the drum rotates.

It has heretofore been proposed to make type and slugs with their two sides radial or wedge-shaped, so that they may be mounted around a drum like the voussoirs of an arch, but with members so formed there is a constant tendency of the pressure to force some type or slug outwardly, and, as soon as any member moves outwardly it loosens the form. Moreover, if the form is locked up and any type or slug is projecting farther than the others, the locking prevents it being forced inwardly to its seat. Accordingly, it has resulted that, with such character of type bodies, either the form was loose or some portion of the form projected farther than other portions, producing a bad printed impression. My type bodies are arranged to seat around the drum with an engagement with each other similar to that which parallel sided slugs or type have when resting on a flat bed, and thus there is no tendency to squeeze out any member, or, if one does move toward or from its seat, it does not vary the position of the rest of the form.

I accomplish the desired result by forming the type body with each of its sides in two planes, one plane being parallel with the central plane of the type body itself, (i. e., at right angles to the foot and face of the type) and the other plane being parallel with the central or radial plane of the adjacent type body standing on the periphery of the drum on which the type bodies are designed to seat. I prefer to sub-divide the side surfaces of the type body into several sections, which are alternately of these self-parallel and adjacent bar-parallel characteristics. Furthermore, I prefer to make the inclined planes on one side of the body op-

posite the rectangular plane on the opposite side. Type bodies so formed may be locked up about the periphery of a drum. The side surfaces which are at right angles to face 60 and base form ribs which extend into the grooves formed by the inclined planes. It thus results that the outermost planes of the two sides of the body are parallel with each other and hence, though the bodies may be 65 locked up in an arcural or circumferential form, still the engagement of each bar with those on opposite sides thereof is in parallel planes, enabling the body to be slid in or out without disturbing the adjacent bodies. 70

Another characteristic of type bodies formed in accordance with this invention is that they may be used at will about a drum or on a flat bed, it being only necessary when they are used on a flat bed to place leads, or 75 other separating strips between them, so that the ribs will not be able to enter the grooves.

Line slugs embodying this invention may be made of ordinary linotype manufacture, having parallel sides, and the inclined portions may be formed by cutting into those sides up and down grooves, which, at the top, have no depth, and at the bottom have a depth corresponding to the amount which the distance between the central radial planes 80 of adjacent slugs at the top of the slugs exceeds the distance between those planes at the bottom of the slugs. It is obvious that slugs may be so cast originally, or cast with parallel sides and the grooves machined 85 afterward.

The drawings clearly illustrate my invention, Figures 1 and 2 being perspective views of the slugs looking at opposite sides thereof; Fig. 3 is an edge view of several 95 of the slugs mounted about the periphery of the drum; Fig. 4 is a plan of several of the slugs mounted on a flat bed or galley; Fig. 5 is an edge view of the slug so mounted; Fig. 6 is a bottom view of the slug; Fig. 7 100 is a diagram on an enlarged scale, illustrating the direction of the inclined side portions of the slugs.

As shown in the drawings, 1 represents the slug having portions 2 on one side, which are parallel with the central or radial plane of the slug, or at right angles to the top and bottom, and between these portions are sections 3, which are parallel with the central or radial plane of the adjacent slug seating 110 on a drum having the intended diameter. On the other side of the slug are surfaces

4, parallel with the slug's radial plane, and these surfaces alternate with surfaces 5 parallel with the radial plane of the adjacent slug. The surfaces 4 parallel with the central plane of the slug itself on one side are opposite the inclined surfaces 3 on the opposite side. Similarly, the surfaces 2 parallel with the central plane are opposite the surfaces 5. This is clearly illustrated in Fig. 6. It will be noted also that the ribs and grooves are of substantially the same width runningwise of the type.

Fig. 7 shows the type bodies on an enlarged scale and the directions of their side planes with reference to the center of the drum for which they are designed. Five type bodies are shown indicated by 1^a, 1^b, 1^c, 1^d and 1^e respectively. Consider for example the second type body from the right, 1^b; its ribs 2 and 4 are parallel, as shown by the lines A and B which continue in the planes of these ribs until tangent to a construction circle C, the diameter of which is equal to the width of the type body. The bottom of the grooves 3 on the right hand side of the type body 1^b are in a plane indicated by D, which is tangent to the left side of the circle C while the bottom of the grooves 5 on the left side of the body 1^b are in a plane, indicated by E, which is tangent to the right side of the circle C. Now as the circle C has a diameter equal to the width of the type, the radius is of course equal to half the width so that a plane through the center of the circle C and the center of the type body 1^b (that is a radial plane F) will be distant half the width of a type from the plane D, and hence be parallel therewith. Similarly the radial plane G of the type body 1^c is parallel with the plane E. This shows that one portion of each side of a type bar is parallel with the central plane of the body itself, and the other portion of each side is parallel with the central plane of the adjacent body.

Instead of considering the characteristics of a type body with reference to the adjacent body, as in the above explanation, these characteristics may be defined in terms of the type body itself and the radius of the drum on which they are designed to seat. Thus, referring to the type 1^a in Fig. 7, the plane of the face of the ribs 2 (the plane A) is tangent to the central circle C at the right hand side of the center, while the plane D, defining the bottom or face of the groove 3, is tangent to the same circle on the other side. Therefore, a radial plane from the center of the drum to the intersection of the planes A and D (that is, to the outer corner of the type body) must bi-sec the angle of those planes and at all points be equi-distance therefrom. From this it follows that the face of the grooves stands back from the plane of the ribs at any point twice

the distance the radial plane through the outer corner of the type body stands back from such plane of the rib face.

The above defined characteristics may be conveniently put in algebraic form. Referring to Fig. 7, let k indicate the distance from the central plane of the type body to either of the planes bounding the sides; that is, to what may be called the rib plane, and let R indicate the radius of the drum. These factors are constant for any particular type body. Now, let t indicate any portion of the height of the type from the bottom up and t' the remainder of the height; x the variable distance from the central plane of the type to the bottom face of the groove, and y the variable distance from the central plane to the radial plane through the outer corner of the type. Now, as this radial plane (y) bi-sects the angle of the rib plane (k) and the grooved plane (x), it follows that the distance between the grooved plane and the rib plane is represented by $2(k-y)$ and hence

$$x = k - 2(k-y), \quad 90$$

or

$$x = 2y - k.$$

Now, by similar triangles, the distance at the outer end of the type body between the central plane and the outer corner (k) must bear the same ratio to y at any point in the height of the type (that is the point between t and t') as the distance from the outer corner of the type to the center of the drum is to the distance from the selected point of measurement for y to the center of the drum. Therefore,

$$k:y = t:t+R:t+R,$$

or

$$y = k \left(\frac{t+R}{t'+t+R} \right). \quad 105$$

Now, substitute y in the above formula of $x = 2y - k$, we have

$$x = 2k \left(\frac{t+R}{t'+t+R} \right) - k, \quad 110$$

or

$$x = k \left(\frac{R+t-t'}{R+t+t'} \right). \quad 115$$

This gives us, therefore, the depth or the distance from any point in the face of the groove to the central plane of the type in terms of the height and thickness of the type and the radius of the drum.

7 represents the character on the edge of the body, which may be cameo or intaglio or planographic, according to the work to be done.

8 and 9 represent notches formed in the opposite ends of a type slug, which provide means for receiving a suitable flange to hold them in place on a drum. It is to be understood that these notches are illustrative of any suitable holding means.

130

In Fig. 3, the broken line 10 represents a portion of the periphery of a drum. When my type bodies are mounted about this drum the ribs 4 nest in the grooves 3 and the ribs 5 in the grooves 5, so that the bodies lock up as if they were wedge-shaped, except that there is no tendency to squeeze any type body outwardly. A type body may be drawn outwardly, as shown in one instance in Fig. 10 3 without displacing the bodies which engage it, as the bearing surfaces are parallel with the central plane of the body. This enables the bodies to be put approximately in place and locked by flanges entering the 15 grooves 8 and 9, and then, as the drum rotates, the pressure of the platen will force the bodies tightly against the face of the drum, thus giving an even impression. No matter how tightly the bodies are forced 20 against each other, there is no tendency to squeeze them outwardly, nor any tendency to hold a body from seating on a drum.

I prefer to make the number of grooves on one side of the slug different from the number on the other. This prevents the bodies being nested together on a drum in either 25 of two directions, but, on the contrary, requires them to stand with their characters in only one direction, so that there is no 30 danger of locking up a body with the character up-side-down. If the total number of ribs and grooves on the side of the body is an odd number, this characteristic of dissimilarity of the two sides will necessarily 35 result. The drawing, for example, shows three ribs, designated 2, and two grooves 3 on the other side, but on the other side there are two ribs designated 4 and three grooves 40 designated 5. Obviously, the nesting effect would not take place if the slug were turned around, so that its two ribs 4 would come 45 against the two ribs 4 of the adjacent slug.

Figs. 4 and 5 show how my type bodies may be mounted on a flat bed. It is only 50 necessary to place between them leads or strips, indicated by 11, which prevent the ribs on one type bar entering the grooves of the next. Accordingly, the ribs on one side of the body engage one lead and the ribs 55 on the other side engage the next lead, and these two sets of ribs being parallel, the type bodies may be firmly locked up, the same as if there were no grooves.

Having thus described my invention, 55 what I claim is:

1. A type body adapted to seat on a drum and having its opposite sides each formed in two planes, one of which is parallel with the central plane of the body and the other 60 of which is parallel with the central plane of an adjacent body on said drum.

2. A type body of the character described 65 having suitable character or characters on one edge and having its sides formed in sections, one section having its surface parallel

with the central plane of the body and the adjacent section having its surface inclined inwardly.

3. A type body having characters on one edge and having the opposite sides formed 70 of sections, some of which are parallel with the central plane of the type body and others of which are parallel with the central plane of a similarly formed adjacent body standing at an angle to the body first mentioned. 75

4. A type body made of a single piece of metal having a character on its edge and having its sides formed of alternate ribs and grooves to present portions which have 80 their surface parallel with the central plane and portions which are inclined, the inclined portions on one side coming opposite the parallel portions on the opposite side.

5. A type body having a character on its edge and having its sides formed of alternate 85 ribs and grooves to present portions which have their surface parallel with the central plane and portions which are inclined, the inclined portions on one side being different in number from the inclined 90 portions on the opposite side.

6. A type body having its opposite sides formed of alternate ribs and grooves, the ribs having surfaces parallel with the central plane of the body, the grooves having 95 surfaces inclined inwardly from the edge of the body continuously to the base.

7. A type body adapted for mounting about a drum and having two sets of surfaces on each side, one set being in a plane 100 parallel with a set on the opposite side, and the remaining sets being parallel with the central planes of adjacent type bodies standing at angles to the body first mentioned on opposite sides thereof respectively. 105

8. A slug adapted for mounting about a drum and having two sets of surfaces on each side, one set being in a plane parallel with a set on the opposite side, and the remaining sets being inclined inwardly, the 110 parallel and inclined sets of surfaces alternating on each side and being staggered with reference to the two sides.

9. A slug having its side surfaces made up of alternate portions in planes parallel with 115 the central plane of the slug and in planes parallel with the central planes of similar adjacent slugs, and shoulders on the ends of the slugs whereby they may be held in place.

10. A printing surface made up of a series of typeholders adapted to be mounted on a drum, each bolder having its side surfaces made up of portions parallel with the central plane and portions inclined inwardly, the inclined portions on one side coming opposite the parallel portions on the other, the number of parallel portions on one side being different from the number of parallel portions on the opposite sides. 120 125 130

11. A printing surface made up of a series of type bodies standing radially about a center, each type body having its side surface formed of different planes, one of which is parallel with the central plane of the body and the other of which is parallel with the central plane of a contiguous similar body standing radially about the same center.
12. A type body of the character described having its opposite sides each formed in two planes, one of which is parallel with the central plane of the body and the other of which is parallel with the central plane of a similar adjacent body nesting against the side of the body first mentioned.
13. A type body having a character or characters on its edge and having its sides formed of alternate ribs and grooves, the grooves having their greatest depth at the base of the body and petering out at the shoulder thereof and intermediately lying in a plane which is at an angle to that of the face of the ribs.
14. As a new article of manufacture, a type body for use on a round or flat surface and having its sides formed with alternate ribs and grooves extending from the base of the body to the shoulder thereof, the surface of the ribs being parallel with the central plane of the body and the grooves being deepest at the base of the body and petering out at the shoulders.
15. As a new article of manufacture, a type body for use on a round or flat surface and having its sides formed with alternate ribs and grooves extending from the base of the body to the shoulder thereof, the surface of the ribs being parallel with the central plane of the body and the grooves being deepest at the base of the body and petering out at the shoulders, the ribs and grooves having substantially the same width running-wise of the type and the ribs on one side of the body being opposite the grooves of the other side.
16. As a new article of manufacture, a line slug having its sides formed of alternate up and down ribs and grooves located side by side, the surface of the ribs being parallel with the center plane of the slug, and the groove being deepest at the base and petering out at the shoulders.
17. As a new article of manufacture, a line slug having its sides formed of alternate up and down ribs and grooves located side by side, the surface of the ribs being parallel with the central plane of the slug and the groove being deepest at the base and petering out at the shoulders, the total number of ribs and grooves on either side of the slug being an odd number.
18. As a new article of manufacture, a line slug having its sides formed of alternate up and down ribs and grooves located side by side, the surface of the ribs being parallel with the central plane of the slug, and the groove being deepest at the base and petering out at the shoulders, the running-wise width of the ribs being substantially equal to the running-wise width of the grooves.
19. A type body having ribs and recesses on its sides the distance from any point in the face of the recess to the plane coincident with the face of the ribs on that side being equal to twice the distance from such plane to a radial plane through the outer corner of the type.
20. As a new article of manufacture, type bodies adapted to seat snugly about the periphery of a drum, each type body having its sides made up of ribs and recesses, the distance from the central plane of the type to any point in the face of the recess being equal to

$$k \left(\frac{R + t - t'}{R + t + t'} \right)$$

where k is half the thickness of the type, R is the radius of the drum, and t and t' the distances from the point of measurement to the inner and outer ends of the type body respectively.

21. As a new article of manufacture, a type adapted to stand on the periphery of the drum compactly with other similar type, said type having its sides composed of ribs and recesses, said ribs being parallel with the central plane of the type and the recesses having their faces at an acute angle to such plane and in such a direction that the radial plane from the center of the drum through the intersection of the two planes defining the face of the rib and the face of the recess respectively bi-sects the angle between such two defining planes.

22. As a new article of manufacture, type designed for use on the periphery of a drum compactly with other similar type, said type having ribs and recesses on its sides, the distance from any point in the face of the recess to the central plane of the type being equal to $2y - k$ where y equals the distance from the central plane of the type to a radial plane from the center of the drum through the outer corner of the type, and k equals half the width of the type at such outer corner.

In testimony whereof, I hereunto affix my signature in the presence of two witnesses.
